United States Patent Office

Des. 200,878
Patented Apr. 13, 1965

200,878

PAIR OF NOVELTY EYEGLASSES

John Arthur Stoddart, 5024 N. 34th St., Phoenix, Ariz.

Filed May 14, 1964, Ser. No. 80,006

Term of patent 3½ years

(Cl. D57—1)

Fig. 1

Fig. 2

Fig. 3

FIG. 1 is a front elevational view of a pair of novelty eyeglasses showing my new design;

FIG. 2 is a lefthand side elevational view thereof; and

FIG. 3 is a top plan view thereof, taken on a reduced scale.

The side not shown is a mirror image of the side shown.

I claim:

The ornamental design for a pair of novelty eyeglasses, as shown and described.
